UNITED STATES PATENT OFFICE.

EDWARD G. MYERS, OF LINCOLN, ILLINOIS, ASSIGNOR OF ONE-HALF TO C. A. RICHMOND,
OF PEORIA, ILLINOIS.

OIL-BURNER.

1,188,010.

Specification of Letters Patent. Patented June 20, 1916.

Application filed June 18, 1915. Serial No. 34,873.

To all whom it may concern:

Be it known that I, EDWARD G. MYERS, a citizen of the United States, residing at Lincoln, in the county of Logan and State 5 of Illinois, have invented a new and useful Oil-Burner, of which the following is a specification.

The device forming the subject matter of this application is adapted to be employed 10 for converting oil into gas and for burning the gas thus produced.

One object of the invention is to effect an improvement in the general construction of the device in so far as is concerned the means 15 whereby the oil or other fuel is converted into gas, distributed and consumed.

Another object of the invention is to improve the generator conduit which lies within the contour of the burner head.

20 A further object of the invention is to provide novel means whereby surplus or unconverted fuel is held back from entering the gas distributing receptacle.

It is within the province of the invention 25 to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the 35 invention herein disclosed can be made within the scope of what is claimed, without departing from the spirit of the invention.

In the drawings:—Figure 1 is a top plan; Fig. 2 is a section taken on the line 2—2 of 40 Fig. 1; Fig. 3 is a top plan showing a modification, parts being in section; Fig. 4 is a section on the line 4—4 of Fig. 3.

In carrying out the invention as shown in Figs. 1 and 2 there is provided a distributing receptacle 2 supported on legs 1 or in any other desired manner, the receptacle 2 having a conical bottom 44 and being provided with a marginal flange 3. By means of bolts 4 or other connecting elements the 45 flange 3 is united with a flange 5 constituting a part of a head 6 having perforations 7. A foraminous partition 8 is bound between the flanges 3 and 5 and extends across the perforations 7. An upstanding rim 9 is 50 carried by the head 6 and clips 10 on the

rim retain a loop-shaped generator pipe 11, one end 12 of which carries a valve casing 14, the valve of which is controlled by an operating device 16. An oil supply pipe 15 of small diameter communicates with 60 the casing 14. The other, depending end 17 of the generator pipe 11 enters a horizontal gas delivery conduit 18 having an upturned end which communicates with the distributing receptacle 2 at the lowermost 65 point of the bottom 44 thereof. The conduit 18 is intersected by an air supply pipe 19 one end of which is open as shown at 20. One end of the conduit 18 carries a gland 22 in which is mounted a threaded needle 70 valve 23 co-operating with a seat 24 mounted in the conduit 18, the valve 23 being controlled by a suitable operating device 25. Depending from the conduit 18 is a stem 26 upholding a primary pan 27. A charge 75 of fuel may be placed in the pan 27 and be ignited at the starting of the device in order to produce an initial supply of gas.

Oil flows by way of the pipe 15 into the generator pipe 11 and is converted into gas 80 which is delivered through the conduit 18 into the distributing receptacle 2, the gas passing through the openings 7 in the head 6, and being broken up as it passes through the foraminous partition 8. The gas burns 85 at the openings 7 and heats the oil in the pipe 11. The pipe 19 admits air into the gas before the latter enters the receptacle 2. The supply of gas is controlled by the valve 23, and the valve in the casing 14 controls 90 the supply of oil to the pipe 11.

In the modification shown in Figs. 3 and 4, parts hereinbefore described remain unchanged saving as hereinafter modified. The numeral 28 denotes the distributing receptacle, the delivery conduit appears at 95 29, the foraminous partition is shown at 30 and the head is designated by the reference character 31. The head is provided with burner openings 32. The generating conduit in this form of the invention is, broadly speaking, of loop-shape as before, but comprises two angularly disposed bores 33 and 34 formed in the head. The point of meeting of these bores is shown at 35, and the 100 meeting ends of the bores are closed by a single plug 36 threaded into the edge of the head 31. By removing the plug 36, both of the bores may be cleaned out. In the bore 33 is placed a core 37 which serves to break 110

up the entering oil. The core 37 may be fashioned in different ways but a roll of wire gauze will prove effective for the ends in view. The numeral 38 indicates a nipple threaded into the end of the bore 33 and carrying a valve casing 39, the valve of which is manipulated by any suitable means shown at 40. The oil supply pipe appears at 41. Into the end of the bore 34 is threaded an elbow 42 corresponding to the part 17 of Figs. 1 and 2. At the inner end of the elbow 42 is an upstanding partition 43 which holds back surplus or unconsumed oil and prevents the same from entering the gas delivery conduit 29.

The structure may be used in the exposed condition of Fig. 2, or it may be mounted in a stove, furnace or other heater, under which circumstances the air supply pipe 19 should be long enough to extend through the bottom of the heater. In some instances the heater may be so constructed as to furnish adequate support for the receptacle 2 or 28 without resorting to the use 25 of the legs 1.

The device forming the subject matter of this application is of peculiar utility and novelty in that, in using oil as a fuel, a blue flame is produced, the structure operating without odor and without objectionable noise, it being observed that recourse is not had to wicks, asbestos rings, or elements of a like nature.

Having thus described the invention, 35 what is claimed is:—

1. In a device of the class described, a distributing receptacle; a perforated head carried by the receptacle, the head having straight, acutely disposed bores defining a 40 V-shaped generator conduit in the head, the bores having a common clean-out opening, the axes of the bores intersecting the perimeter of the head within the contour of the opening; a single closure mounted 45 in the opening; means for supplying fuel to one end of one bore; and means for conducting gas from the other corresponding end of the other bore to the receptacle.

2. In a device of the class described, a

distributing receptacle; a perforated head 50 carried by the receptacle; a gas supply pipe opening into the bottom of the receptacle and extended laterally beyond the periphery of the receptacle; a transverse air supply pipe interposed in the gas supply pipe, the 55 upper end of the gas supply pipe being closed and being disposed above the air supply pipe, the lower end of the air supply pipe being open; a seat in the gas supply pipe and disposed outwardly of the air supply pipe; a valve in the end of the gas supply pipe coöperating with the seat; a priming cup disposed below the gas supply pipe and carried thereby, adjacent the outer end of the gas supply pipe; and a gas 60 producing means adapted to be heated by the flames at the perforations of the head and discharging into the gas supply pipe between the outer end thereof and the seat.

3. In a device of the class described, a 70 distributing receptacle; a perforated head carried thereby; a gas supply pipe projecting laterally from the receptacle; a seat in the pipe and coöperating with the outer end of the pipe to form a gas receiving chamber; a priming cup carried by the pipe and disposed below said chamber; a valve in the pipe and coöperating with the seat; and a gas producing means communicating with the pipe, and positioned to be heated 75 by the flames at the perforations in the head.

4. In a device of the class described, a distributing receptacle; a head carried thereby and provided with a loop-shaped 80 generating conduit; means for supplying fuel to one end of the conduit; an elbow mounted in the other end of the conduit and provided at its inner end with an up-standing lip; and a pipe leading from the 85 elbow to the receptacle.

In testimony that I claim the foregoing as my own, I have hereto affixed my signature in the presence of two witnesses.

EDWARD G. MYERS.
